(57) **CLAIM**

The ornamental design for a urine collection assembly, as shown and described.

DESCRIPTION

FIG. 1 is a front, top, perspective view of a urine collection assembly, according to a new design;

FIG. 2 is a top plan view thereof, with the bottom plan view, right side elevational view, and left side elevational view are identical to the top plan view of FIG. 2;

FIG. 3 is a front elevational view thereof;

FIG. 4 is a rear elevational view thereof; and,

FIG. 5 is a rear, top, perspective view thereof.

The broken lines shown in the drawings depict portions of the urine collecting assembly that form no part of the claimed design.

The urine collection assembly is shown with a symbolic break in its length. The appearance of any portion of the article between the break lines forms no part of the claimed design.
